WET REFUSE BURNING GRATE

Louis J. Schrenk, Detroit, Mich.

Application May 25, 1935, Serial No. 23,433

1 Claim. (Cl. 122—2)

This invention relates to a grate, or hearth, for burning wet fuels and, particularly, to such a grate used in conjunction with auxiliary firing as with pulverized fuel.

5 In burning wet fuels, such as garbage, sewage screenings and the like, or mixtures of wet and dry fuels within the furnace of a steam boiler, as is disclosed in my co-pending application, Serial No. 719,637, filed April 9, 1934, I have found that burning is materially improved if the wet fuel is agitated. This application is a continuation in part of said application.

One object of the present invention is to provide in a furnace for burning wet fuels, where 15 combustion is augmented by supplementary fuel, the combination of a fluid-cooled grate and means for agitating the wet fuel, the grate serving to cool and protect the agitating means.

Other objects and advantages of the invention 20 will become apparent upon consideration of the following detailed description and the appended claim when read in conjunction with the accompanying drawings in which:

Figure 1 is a cross-sectional elevation of a 25 boiler and furnace involving the invention.

Figure 2 is a plan view of a portion of the grate;

Figure 3 is an enlarged side elevation partly 30 in section of a portion of the grate and shows the construction and operating means for the fuel agitators in one form thereof;

Figure 4 is a section on line 4—4 in Figure 3.

Figure 5 is a section on line 5—5 in Figure 3.

As shown in Figure 1, the wet refuse is burned 35 on a fluid-cooled grate 10 which is at the bottom of a furnace 11. Another or supplementary fuel is burned and directed into the furnace so that its flame may impinge or pass over the surface of the wet fuel to be burned. Such other 40 fuel may be in the form of a pulverized fuel stream which as shown is directed downwardly by burners 12, the flames 13 descending toward the grate 10, and thence bending upwardly in the shape of a U and leaving the furnace at the 45 upper end. The furnace in this case is surrounded by a steam boiler 14 of a usual type, for absorbing the heat from the gases leaving the furnace.

The grate or hearth 10 comprises a plurality 50 of spaced tubes 15 extending longitudinally of the furnace, the tubes being connected into headers 16 and 17, and thence through downcomers 18 and risers 20 to the steam and water drum 21 of boiler 14 for circulation of boiler water 55 therethrough. At the end of the grate where

the wet fuel enters, the intertube spaces of the grate are covered by blocks or tiles 22, preferably of cast iron, arranged to have air spaces 23, Figure 4. Further down the grate I provide several transverse rows of oscillatable agitators 5 24, and below these the intertube spaces are again covered by similar tiles 22. Compartments 25 may be formed by partitions 26 to divide the air space beneath the grate into zones delivering air at different volumes and pressures through 10 the related sections of the grate.

The wet fuel, in this case garbage or a mixture 15 of garbage and rubbish, enters through the hoppers 27 of a feeding mechanism which, in this case, consists of a multiplicity of reciprocable feeding rams 28, which are arranged in horizontal alignment across the grate. The rate of feed 20 may be varied by the number of strokes the rams make in a given time. From the hoppers 27, the wet fuel falls in front of the feeding rams 28, 25 on their rearward stroke, and is pushed into the furnace 11 onto the grate 10 on the forward stroke of the rams. On the grate the fuel may assume the general shape shown in Figure 1. The flames 13 of the supplementary fuel stream 25 sweep over the wet fuel bed in a direction opposite to that of the wet fuel travel down the grate and the high temperature of these flames supplies the heat for drying and igniting the wet fuels.

I have found that combustion of the wet fuel 30 may be materially improved by providing the agitators 24 which are adapted to be oscillated through an angle of 90° to turn the fuel bed over so that its constituents may be thoroughly 35 and repeatedly exposed to the drying and consuming action of the flames in the furnace. The agitators are, preferably, made of iron or steel in the forms of sectors of a circle and arranged in rows, in this instance three, transversely of 40 the grate.

As shown in Figure 3, the agitators are in the 45 form of quadrants oscillatable about pivot pins 30 carried by cast iron or steel plates 31 supported on and between pairs of grate tubes 15, 45 Figure 5. The plates 31 are formed with slots 32 through which the agitators are oscillatable and which are normally occupied by the apertured radially extending top surfaces 33 of the agitators that support the wet fuel as it passes there- 50 over down the grate. The apertured top surface 33 of each agitator 24 comprises a series of inclined overlapping slats or plates 34 spacedly mounted between sectional side plates 35 of the agitator. The top plates 34 are disposed at a 55

downward angle to the upper radial edge 33 of the agitator so that the apertures or passages 36 resulting from their overlapped and spaced relation are inclined reversely to the direction of movement of the fuel bed. The overlapping relation of plates 34 and the inclination of passages 36 not only prevents the fuel dropping through an agitator into the air compartments 25 but also directs air admitted from the latter to and through the fuel bed in such a manner as to cause the air pressure to assist in moving the fuel along the grate. When an agitator is swung into the furnace, the side plates 35 depending below the top plates 34 and an arcuate plate 37 mounted between the plates 35 maintain the slot 32 in plate 31 closed. This results in preventing air being blown into the furnace through the sides and ends of the agitators and also precludes fuel falling through the latter from adjacent portions of grate 10.

The number of agitators 24 in each transverse row depends on the width of the furnace. All of the agitators in a transverse row may be operated by a pressure cylinder 40, or the agitators of a row may be divided into groups operable by cylinders individual to the respective groups. Each agitator is connected by a linkage 41 to a rock shaft 42 operable in turn by the piston associated with the cylinder 40 through a linkage 43. The valves 44 for controlling the operation of the several transverse rows of agitators, or the groups of each row, may be conveniently located, as at the side of the furnace, for manual control. If desired the valve control members 45 may be mechanically or electrically connected with the operating mechanism of rams 28 for automatic actuation in any desired relation to the latter.

As the wet fuel is fed into the furnace it is exposed to the drying and consuming action of the flames in the furnace as it is advanced along the grate on the introduction of successive charges by the rams 28. The air jets directed through passages 36 in the agitators 24 not only supply air for combustion but also assist in drying

the wet fuel and moving it along the grate. When the agitators 24 are oscillated they act to push the wet fuel downwardly through the grate and in doing so turn the wet fuel bed with which they come in contact entirely over, thereby increasing the rapidity with which the wet fuel is dried and also breaking up the crust formed over the surface by the burning of the wet fuel and the supplementary fuel.

Should the supply of wet fuel to the furnace be low, relatively more supplementary fuel will be burned to maintain the output rate of the boiler and should the wet fuel supply cease, the supplementary fuel alone would be used. In either case, the wet fuel grate and the agitators would be subject to considerable heat, since the protection of the wet fuel is then minimized or may even be removed. Under such circumstances the fluid-cooled tubes of the grate absorb sufficient heat, mostly by radiation from the agitators, to protect them from burning or warping.

Although an illustrative embodiment of my invention has been shown and described in detail herein, there are many changes and variations that may be made without departing from the invention and which I, therefore, desire and intend to include within the scope of the following claim.

What I claim is:

In a refuse burning boiler and furnace installation having a boiler, a combustion chamber, an inclined perforate hearth in said chamber, means for feeding refuse to the hearth and means for supplying air under pressure through the hearth and the bed of refuse thereon; a plurality of pivoted agitators interposed in the hearth and operable to advance the fuel therealong, said agitators each having fuel contacting surfaces including a plurality of plates disposed horizontally and arranged in overlapped relation with their adjacent ends spaced to form a plurality of air passages inclined relatively to the surface of said hearth for directing air flowing through said passages under pressure in such manner as to assist in moving the fuel along the hearth.
